UNITED STATES PATENT OFFICE.

ELI FRANK CRABTREE, OF BALTIMORE, MARYLAND.

DESIGN FOR A DIRECTION-SIGNAL CASING.

Application filed February 23, 1922. Serial No. 848. Term of patent 3½ years.

To all whom it may concern:

Be it known that I, ELI FRANK CRABTREE, a citizen of the United States, residing at Baltimore, in the State of Maryland, have invented a new, original, and ornamental Design for Direction-Signal Casing, of which the following is a specification, reference being had to the accompanying drawing, forming a part thereof.

Fig. 1 is a front elevation of the article, showing my new design.

Fig. 2 is a rear elevation thereof.

Fig. 3 is an end view thereof.

I claim:—

The ornamental design for a direction signal casing as shown.

ELI FRANK CRABTREE.
